UNITED STATES PATENT OFFICE

HENRY T. HAYS, OF LEXINGTON, INDIANA.

GRADING-MACHINE.

SPECIFICATION forming part of Letters Patent No. 276,583, dated May 1, 1883.

Application filed December 4, 1882. (No model.)

To all whom it may concern:

Be it known that I, HENRY T. HAYS, of Lexington, in the county of Scott and State of Indiana, have invented a new and useful Improvement in Grading-Machines, which shall be simple in construction, inexpensive in manufacture, and convenient and effective in use.

Similar letters of reference indicate corresponding parts.

10 The accompanying drawing represents a perspective view of my invention.

a represents the scraper-blade, upon the top of which are mounted the two standards *b*, which are slotted at their upper ends for the 15 vertical adjustment of the handles *c*. In between the upper ends of the standards is bolted the plate *h*, which has its ends turned at right angles, and through these ends, the standards, and the handles are passed the clamping-bolts 20 which secure the handles in place. Secured to the standards at their lower ends, and to the handles, are the braces *e*, which serve to draw the scraper-blade along and prevent it from giving backward. The handles *c* are 25 extended forward and form both handles and

beams, and are loosely fastened at their front ends to the bolster-coupling *f*, which is intended to be attached to a harrow by means of the bolt *y*. Secured to this bolster are the two flat springs *g*, which keep the blade forced 30 constantly downward, so as to sink through the dirt which has been loosened by the harrow, which is drawn along in front.

The harrow or cultivator for loosening the earth is not here shown, as it forms no part 35 of my invention.

Having thus described my invention, I claim—

1. In a grading-machine, the combination of the scraper-blade *a*, the standards *b*, combined 40 handles and beams *c*, bolster *f*, and springs *g*, substantially as shown.

2. In a grading-machine, the combination of the blade *a*, standards *b*, plate *h*, combined 45 handles and beams *c*, braces *e*, bolster *f*, and springs *g*, substantially as set forth.

HENRY T. HAYS.
